UNITED STATES PATENT OFFICE.

JOHN E. WARD, OF NEW YORK, N. Y., ASSIGNOR TO WARD EQUIPMENT COMPANY, OF NEW YORK, N. Y., A CORPORATION OF NEW YORK.

TERMINAL-PLUG RECEPTACLE.

972,956.

Specification of Letters Patent. Patented Oct. 18, 1910.

Application filed July 9, 1909. Serial No. 506,708.

To all whom it may concern:

Be it known that I, JOHN E. WARD, a citizen of the United States, and a resident of the borough of Manhattan of the city of 5 New York, in the county and State of New York, have invented certain new and useful Improvements in Terminal-Plug Receptacles, of which the following is a specification, reference being had to the accompanying 10 drawings, forming a part hereof.

The improvements have been devised with particular reference to the charging of storage batteries located upon railway cars and used for heating, lighting or for any other 15 purposes. It is customary, in car yards, to connect the cars as they stand idle with an electric main for the purpose of charging their storage batteries, and in such charging systems, there is usually what is called a 20 yard plug which is electrically connected with the main and which is adapted to be inserted into a terminal socket upon the cars to be charged, for the purpose of making the circuit complete from the main to 25 the batteries.

The object of the present invention is to provide a simple and convenient socket or receptacle which shall be particularly adapted to meet the conditions of use of 30 such terminals as they exist upon railway cars which are charged through a yard plug in the car yard.

The details of the invention will now be described in connection with the accompanying 35 drawings in which—

Figure 1 is a view in central vertical section through a receptacle embodying the invention, and, Fig. 2 is a similar view of the casing of the receptacle taken on a plane at 40 right angles to that of Fig. 1.

The improved receptacle is secured upon the bottom of the car or to any other convenient part through a bracket *a* to which the casing *b* of the receptacle is fastened by 45 means of a bolt *c*, the latter being arranged to act as a pivot so that the casing may be adapted to face in any direction. In the present case the bolt extends through what may be referred to as the cover portion of 50 the casing to which the body portion, which envelops the electrodes, is secured through bolts *d*.

The electrodes, which may be one or more in number (two in the present case) are 55 shown at *e* as being enveloped in an insulat-

ing block *f* and are provided with sockets at each end so that they may receive the plug terminals *g* at one end and the terminals of the storage battery circuit (not shown) at the other end. The latter, it 60 may be stated, are adapted to enter the casing through the openings *h*. The block containing the electrodes is suitably supported in a frame or bracket *i* suspended from the cover plate of the casing and provided with 65 openings at the front and back for the reception of the yard plug and battery terminals respectively.

The yard plug may be of any suitable construction so far as the present invention 70 is concerned, being preferably of the form shown and described in an application for U. S. Patent filed November 28, 1908, Serial No. 464,587. In the present case a plug of this form is shown having, as before stated, 75 the two terminals *g*. This plug fits into an opening in the forward part of the casing of the receptacle so that the terminals may be easily inserted into their electrode sockets in the block *f*.

I claim as my invention:

1. A terminal plug receptacle for railway cars, comprising a bracket, a casing pivoted to the bracket so as to swing horizontally when in position on the car, electrodes, and 80 a frame within the casing to support the electrodes.

2. A terminal plug receptacle for railway cars, comprising a bracket, a casing pivoted to the bracket so as to swing parallel with 85 the car bearing surface of the bracket, a block containing one or more electrodes, and means within the casing to support the block.

3. A terminal plug receptacle for railway cars, comprising a bracket, a casing having 90 a cover plate pivoted to the bracket, a block containing one or more electrodes, and a frame suspended from the cover plate to support the block.

4. A terminal plug receptacle for railway 100 cars, comprising a bracket, a casing having a cover plate pivoted to the bracket and a body portion having openings both at the front and back for the yard plug and battery terminals respectively, a block containing one or more electrodes, and a frame suspended from the cover plate to support the block and also having openings front and back for the yard plug and battery terminals respectively.

110

5. A terminal plug receptacle for railway cars containing insulated socket electrodes for the yard plug terminals and also for the battery terminals, and means for pivotally supporting the receptacle from the car.
6. An electrical connecting member for railway cars comprising in combination means for pivotally supporting to a car a holding means and the holding means carrying an electrode of a plug and socket connection which is to engage a companion

electrode on a yard cable and also carry another electrode of a plug and socket connection which is to engage a companion electrode on a cable carried on the car.

15

This specification signed and witnessed this 7th day of July, A. D., 1909.

JOHN E. WARD.
